UNITED STATES PATENT OFFICE.

CARL ZETTERLUND, OF CHICAGO, ILLINOIS.

HOISTING APPARATUS.

Application filed August 20, 1925. Serial No. 51,500.

My invention relates broadly to hoists or elevating machines used particularly for elevating building material and similar objects to higher levels, say in the construction of buildings, and has particular reference to a machine of this type, which is automatic in the operation of stopping the platforms or cages when reaching a predetermined level. While I shall describe my invention particularly adaptable for elevating building material and similar objects in the construction of a building and automatic in the manner above described, it will be understood that my invention may be used for elevating other objects, whether of similar or dissimilar nature, while on the other hand, it may embody certain features of novelty hereinafter disclosed without being automatic in the operation of stopping the movement of the platforms when reaching the desired level.

The principal object of the invention is to provide a machine of the above mentioned general character, whereby two or more elevating platforms or cages, on which material to be elevated is placed, will be alternately raised by a suitable power apparatus, to the desired level, and will there be automatically stopped.

A further object of the invention is to provide an improved form of construction wherein the power apparatus employed may be controlled from a distance, in the present instance being the level to which the material is elevated, so that outside of the workmen at this level, no workman other than those at this level will be required to operate the machine controlled from a single point, with the result that the machine may be operated with greater safety.

A still further object of my invention is to provide a structure wherein the mechanism for elevating the platforms comprises an improved type of reversing mechanism having a drive shaft provided with gears which mesh with a gear on a drum. This drum may be alternately rotated in reverse direction to wind and unwind the cable leading to the platforms, by means of a clutch member which is shifted to engage either gear with the drive shaft. A neutral position may be obtained by the clutch member, and it is within the scope of this invention to provide an improved form of locking member for locking the clutch member in neutral position, whereby the platforms are held

locked at the level to which they have been carried.

A further object of my invention is to provide an improved form of control whereby when the platforms reach their intended levels, the power is quickly checked and the clutch member is shifted to neutral position. 60

A still further object of my invention resides in an improved form of pawl and ratchet mechanism which prevents accidental reverse rotation of the drum. 65

Other objects and advantages of my invention will be apparent from the following detailed description when taken in connection with the accompanying drawings which 70 form a part thereof.

In the drawings:

Figure 1 is a top plan view of a machine embodying my invention;

Fig. 2 is a side elevation of the same; 75

Fig. 3 is an elevation of the opposite side;

Fig. 4 is a rear view of the elevator frame carrying the platforms;

Fig. 5 is an enlarged sectional view taken horizontally through the reversing mechanism; 80

Fig. 6 is a detail view of the tripping element;

Fig. 7 is a view illustrating a type of prime mover that may be employed herein to provide a suitable form of speed check for the power shaft as either platform descends. 85

Referring more particularly to the drawings wherein I have shown a preferred embodiment of my invention, a base 10 is adapted to carry the uprights or standards 11 which are connected at the top by a cross member 12. A central standard 13 is likewise suitably carried and connected at its top to cross member 12, and between these standards the elevator cages or platforms 14 and 15 are guided for operation. The standards comprise the main supporting frame of the platforms, which frame may be of any suitable size, form and material, but preferably of wood or metal and of a height capable of reaching the desired level to which the platforms are to elevate material, in some instances to ten or more stories, which is quite common in the construction of modern skyscrapers. Supported by the top cross member 12 are the sheaves 16 and 17 about which the ends of a cable 18 are trained for connection to said platforms 14 and 15. This cable is adapted alternately to raise and lower the platforms, and, as a consequence, 110

when one end of the cable is being wound upon a drum 19, the other end is being released, which action results in the raising of one of the platforms and in the lowering of the other.

It is apparent from Figs. 1 and 2 that both strands of cable 18 extend downwardly and under a double grooved pulley 20 suitably supported on base 10, from where said strands 10 are wound in the usual manner around drum 19.

The power for operating the drum 19 and for providing the alternate rotation to lower and raise each cage in proper sequence is obtained through a reversing mechanism carried by a continuously driven power shaft 21. This power shaft may be driven from any suitable source and may be journaled in bearings 22 and 23 carried by the frame members 24, which are supported on base 10. By referring particularly to Figs. 1, 2 and 5 wherein this reversing mechanism is shown in detail, it will be observed that the free end of shaft 21 is axially bored for a distance to accommodate an axially movable rod 25. The inner end of this rod is provided with a right angle bend 26 which projects outwardly through an opening 21^a in rod 21 and to which is fastened a shiftable clutch element 27 guided adjacent its ends by transversely extending apertured lugs 28 suitable fixed upon power shaft 21 for rotation therewith. At this point it will be apparent that the purpose of this clutch element is alternately to engage either one of a pair of dogs 29 and 30 carried by suitable gears 31 and 32 having relative rotation with respect to power shaft 21. Gears 31 and 32 are in constant mesh with a bevel gear 33. This bevel gear may be made integral with drum 19, or it may be formed separately and then fastened thereto in any suitable manner. From the above description it will be observed that the longitudinal shifting or axial movement of rod 25 will alternately engage clutch member 27 with gears 31 and 32, and thereby cause alternate opposite rotation of bevel gear 33 and consequently a similar movement of drum 19.

The successive engagement and disengagement of the gears 31 and 32 with power shaft 21, providing the alternate rotation in opposite directions of the drum 19, is effected through a trip cam 39 adjustably carried on the center standard 13 preferably at one of a series of holes 31'. Said trip cam 39 is fixed on the inner end of a crank 44 extending through the center standard 13 in journaled relation. A grooved pulley 33' may also be carried on this inner end of crank 44 for the purpose of receiving the upper loop of a cable 35, both strands of which cable extend downwardly and under a double sheave 36, these strands being designated 37 and 38 in Fig. 5. The ends of strands 37 and 38 are fastened to the ends of an actuating arm 40 which

may be pivotally mounted in a horizontal position on a lateral projection or shelf 46 carried by the right hand frame member 24.

The outer end of rod 25 is provided with a groove 41 adapted to project through an eye 42 carried by actuating arm 40. Inasmuch as this actuating arm 40 is pivoted to the projection 46 by means of a pivot pin 43, it may be easily swung about its mounting by the strands 37 and 38 whereby the rod will be axially shifted either to bring the clutch member 27 into alternate engagement with the dogs on gears 31 and 32, or to shift the clutch to a neutral position, as shown in Figure 5.

A novel form of locking device may be provided to hold the actuating arm 40 in the position given it by either strand of the cable 35, which locking device comprises a pivotally mounted arm 47 carried at 48 on the frame member 24 and adapted to swing in a vertical plane so as to bring its inner edge into locking engagement in a groove 49 provided in the actuating member 40. It will be observed in Fig. 5 that the actuating member 40 is provided with a lateral extension 50 intermediate its ends and this extension is adapted to carry the pivot pin 43, which mounts the same on projection 46, and is also fitted with this groove 49. A pair of downwardly projecting fingers 51 and 52, somewhat arcuate in formation, are provided on arm 47 to abut against an edge of actuating arm 40, these fingers serving in effect to straddle the lateral projection 50 and engage the actuating arm on the opposite sides thereof. A spring 55 normally tends to hold locking arm 47 in engagement with groove 49. This is accomplished by providing a vertical projection 56 on actuating arm 40 and a similar projection 57 on the locking arm 47. It will be noted that the sides of groove 49 are somewhat curved and that the distance between the actuating arm 47 and the center of pivot pin 43 is less than the distance between the center of this pin and the fingers 51 and 52; consequently, when a pulling force is applied by the strands 37 and 38 of cable 35 to the arm 40 at either end, either finger 51 or 52, depending at which end this pulling force is applied, will tend to force the locking arm 47 out of engagement with groove 49. In other words, the fingers 51 and 52 carried by the locking member 47 tend to hold the actuating arm 40 rigid during the time when the hoist is not in operation, at which time the rod 25 will be holding said clutch member 27 in neutral position.

It will be apparent that when the trip cam 39 is set in either dotted line position, as shown in Figure 6, one of the strands 37 and 38 will be pulled upwardly to pull the corresponding side of actuating arm 40 forwardly, whereupon the rod 25 will shift to engage the clutch member 27 with either of the dogs 29 and 30 on the gears 31 and 32. This action immediately starts the drum 19 to rotate, in

either direction, to raise and lower the elevator platforms 14 and 15. If trip cam 39 is set in the left-hand dotted line position shown in Figure 6, the ascending elevator platform 14 will strike against it and move it to its full line or vertical position as shown in this figure. This immediately causes the strand 37 to bring its end of actuating arm 40 forwardly so that the actuating arm will be in a straight line or at right angles to the axis of rod 26. In this event the clutch member 27 is shifted to its neutral position, as shown in Figure 5, and the drive shaft 21 is disengaged.

Assume that it is desirable to start the hoist operating again, the workmen on the level to which the platform 14 has been carried will, by means of crank 44, swing the trip arm to the right-hand dotted position shown in Figure 6, whereupon the strand 37 continues to pull the corresponding end of actuating arm 40 forwardly to shift the rod 25 inwardly, whereupon the clutch member 27 engages with dog 29 to connect the gear 31 with drive shaft 21. The drum 19 will again rotate, but this time the elevator platform 15 ascends and the platform 14 descends. As soon as platform 15 approaches the level at which the trip cam 39 is mounted on the center standard 13, it will engage this cam to swing it upwardly to a vertical position, whereupon the gear 31 is immediately disengaged from the drive shaft 21. The movement of trip cam 39 from its right-hand dotted line position to its full line position as shown in Figure 6 is just sufficient to shift the clutch member 27 out of engagement with the dog 29. It does not shift the clutch member 27 far enough to engage it with the dog 30; consequently, a neutral position is obtained.

A speed check may be provided to assure a smooth stopping action of the platforms when they reach the limit of their movement and this speed check may comprise a device, as shown in Figs. 4 and 7. A segment member 60 pivotally mounted at 61 at the rear of the center standard 13 has its ends extending in a manner so as to be engaged by either platform 14 and 15 when they move to their lower position. A central vertically projecting arm 62 is furnished on segment 60 and to this arm one end of a cable 63 is fastened. A pulley 64 is mounted below the segment 60 for guiding the cable 63, the latter extending to the source of power, as shown in Fig. 7, so that the speed of the power shaft 21 will be decreased when slack is placed in the cable 63. This is accomplished by either end of the segment 60 moving downwardly by engagement with either of the elevator platforms. A spring 65 tends to maintain the segment 60 in the position shown in Figure 4. Thus the speed of the drive shaft 21 is momentarily checked, which facilitates disengaging the same from the reversing gear mechanism shown herein.

In Fig. 7 I have illustrated one form of control adapted for operation by the speed check. In this form, however, the prime mover, which may, if so desired, be an internal combustion engine 90, drives power shaft 70 21. A throttle valve 91 is provided in the intake manifold of the engine and is held in closed position by a spring 93. This spring may be attached at one end to any suitable permanent frame member, and at the other end to the throttle lever 94. When cable 63 is released by either platform lowering, spring 93 moves lever 94 forwardly to gradually move throttle valve 91 towards closing position and thereby to momentarily check 80 the speed of power shaft 21.

Means may be provided to lock the drum against rotation and thereby lock the elevator platforms against movement when it is desired to hold them at a certain level. This mechanism comprises a pawl and ratchet arrangement and may be embodied in the form shown in the drawings wherein the peripheral edges 70 and 71 of the drum 19 are toothed and are adapted to be engaged by pawl members 72 and 73. The position of these pawl members is controlled by the movement of the actuating arm 40. I prefer to mount the pawls in fixed relation on a pin 75, which may be suitably carried in a bearing 76 extending 95 from the frame member 24. A link 77 connects the pin 75 with one end of actuating arm 40 whereby movement of this arm rotates the pin to swing the pawls 72 and 73 into and out of engagement with the ratchets 70 and 71 respectively. Link 77 may be slotted so as to allow for a loose connection with the pawl 72, this being had by means of a pin 78 extending from the pawl 72 and riding in a slot 79 in the link 77. The drum 19 may be mounted upon a vertical support 80 extending upwardly from the base 10. A suitable bolt 81 may pass centrally through the drum 19 to clamp the latter to the supporting member 80. The outer end of bolt 81 is reduced 105 and receives one end of a spring 82. This spring provides a snap action for the pawls 72 and 73 in their engagement with the ratchets 70 and 71. When either pawl is moved past the dead center line, the spring accelerates the movement and tends to hold the pawl in engagement with its cooperating ratchet. The opposite end of spring 82 is secured to the outer end of an arm 83 carried by these pawls. 110

From the foregoing description, the operation of my invention will be obvious. Assume that the machine is about to be operated to raise and lower the platforms 14 and 15 in their proper order. The workman operates crank 44 to swing the trip cam 39 to a horizontal position, whereupon the drive shaft 21 is engaged with either of the gears 31 and 32. This rotates the bevel gear 33 and drives the drum to unwind one strand and to wind the 115 120 125 130

other strand of cable 18. The elevator platforms 14 and 15 will then be raised and lowered in alternative relation. When these platforms approach the desired level, the drive shaft 21 is automatically disengaged and the operation of the hoist stops. This automatic feature is the result of one of the platforms engaging the trip cam 39. The clutch member of reversing mechanism will remain in neutral position during this time and will not again engage the drive shaft until the crank 32 is operated to swing the trip cam to horizontal position.

Without further elaboration, the foregoing will so fully explain the gist of my invention, that others may, by applying current knowledge, readily adapt the same for use under varying conditions of service without eliminating certain features which may properly be said to constitute the essential items of novelty involved, which items are intended to be defined and secured to me by the following claims.

I claim:

- 25 1. A hoist of the type described including a plurality of opposed platforms adapted to be alternately raised and lowered and provided with a reversible drive, and means for engaging and automatically disengaging said drive to start and stop the movement of said platforms, said means being operable in different positions at the level at which said platforms are elevated and engageable by said platforms to disengage said drive.
- 30 2. A hoist of the type described including a plurality of opposed platforms provided with a reversible drive and means for automatically disengaging said drive when either of said platforms reaches a predetermined level, said means being positioned alternately at said level for engagement with said platforms as they are alternately raised and lowered.
- 35 3. A hoist of the type described including a plurality of opposed platforms provided with a reversible drive and means for automatically disengaging said drive when either of said platforms reaches a predetermined level, said means being positioned at said level and adapted to have a plurality of positions for a tripping engagement with either ascending platform, the movement to either position serving to re-engage said drive.
- 40 4. A hoist of the type described including a plurality of platforms, a reversible drive, means for automatically disengaging said drive when either of said platforms reaches a predetermined level, and a speed check operable to slacken the speed of said drive as either platform approaches the limit of its downward movement.
- 45 5. A hoist of the type described including a plurality of platforms, a reversible drive, means for automatically disengaging said drive when either of said platforms reaches a predetermined high level, said means being

disposed in the vicinity of said high level so as to be automatically tripped by engagement with either platform when approaching the limit of its upward movement, and a speed check operable to slacken the speed of said drive as either platform approaches the limit of its downward movement, said speed check being also disposed in the path of movement of said platforms for engagement thereby.

6. In a hoist of the type described, the combination with a continuously operated drive shaft, of a reversing mechanism driven by said drive shaft, a plurality of platforms adapted to be elevated alternately by the engagement of said reversing mechanism with said drive shaft, a drum, cables leading from said drum to said platforms, a tripping element alternately disposed in the path of said platforms, and means connecting said tripping element with said reversing mechanism for automatically disengaging the latter from said drive shaft when either platform engages said tripping element.

7. In a hoist of the type described, the combination with a source of power, of mechanism for alternately raising and lowering a plurality of elevator platforms, an adjustably mounted tripping element adapted to be positioned at the level to which said platforms are elevated, an actuating arm for controlling said mechanism, and flexible connections between said tripping element and said actuating arm whereby said mechanism may be operated to engage and disengage said source of power according to the position of said tripping element.

8. In a hoist of the type described, the combination with a source of power, of mechanism for alternately elevating a plurality of elevator platforms, a tripping element controlled by the movement of said platforms, an actuating arm operable by said tripping element to engage and disengage said source of power, and a locking element normally tending to lock said actuating arm in power disengaging or neutral position.

9. In a hoist of the type described, the combination with a source of power, of mechanism for alternately elevating a plurality of elevator platforms, a tripping element controlled by the movement of said platforms, an actuating arm operable by said tripping element to engage and disengage said power, flexible connections between said tripping element and said actuating arm, said tripping element being positioned for engagement by said platforms when elevated whereby automatically to disengage said power.

10. In a hoist of the type described, the combination with a drive shaft, a plurality of elevator platforms adapted to be alternately raised and lowered, a drum, a cable extending between said elevators and drum, mechanism for interconnecting said drive

- shaft to said drum whereby to wind and unwind said cable therefrom; said mechanism comprising a beveled gear carried by said drum, gears carried on said drive shaft in mesh with said beveled gear but normally disengaged from said shaft, and means for engaging said gears and said shaft, including an axially cored end on said shaft and a shiftable element in said core, a clutching member carried in projected relation by said shiftable element and between said gears, and means for actuating said shiftable element.
11. In a hoist of the type described, the combination with a plurality of elevator platforms adapted to be alternately raised and lowered, of mechanism for raising and lowering said elevator platforms comprising a drive shaft, a drum adapted during operation to be driven by said drive shaft, gears on said drive shaft, a bevel gear connected to said drum, means for alternately engaging said gears with said drive shaft, and a pawl device actuated by said means and cooperating with said drum to prevent accidental rotation of said drum.
12. In a hoist of the type described, the combination with a plurality of elevator platforms adapted to be alternately raised and lowered, of mechanism for raising and lowering said elevator platforms comprising a drive shaft, a drum adapted during operation to be driven by said drive shaft, gears on said drive shaft, a bevel gear connected to said drum, and an actuating arm operable by the movement of said elevator platforms first to engage one of said gears with said drive shaft, then to shift the driving connection to neutral position, and thereafter to engage the other gear with said drive shaft to reverse the rotation of said drum.
13. In a hoist of the type described, the combination with a plurality of elevator platforms adapted to be alternately raised and lowered, of mechanism for operating said elevator platforms comprising a drive shaft having gears thereon normally disengaged therefrom, a drum, a gear connected thereto in mesh with said gears, an actuating arm pivotally mounted adjacent said drive shaft, a shiftable clutch element connected to actuating arm, and means operating said actuating arm whereby said shiftable clutch element may engage either of said gears with said shaft.
14. In a hoist of the type described, the combination of a plurality of elevator platforms adapted to be alternately raised and lowered, of mechanism for operating said elevator platforms comprising a drive shaft, a drum, and reversing mechanism therebetween alternately to engage and disengage said drive shaft, an actuating arm controlled by the movement of said elevator platforms, cables extending from said elevator plat-
- forms to said drum, and a pawl and ratchet device controlled by said actuating arm for said drum.
15. In a hoist of the type described, the combination of a plurality of elevator platforms adapted to be alternately raised and lowered, of mechanism for operating said elevator platforms comprising a drive shaft, a drum, and reversing mechanism therebetween alternately to engage and disengage said drive shaft, an actuating arm controlled by the movement of said elevator platforms, cables extending from said elevator platforms to said drum, said drum being grooved to receive said cable, teeth formed on the peripheral edges of said drum, and a double acting pawl device actuated by said arm to prevent accidental backward rotation of said drum.
16. In a hoist of the type described, the combination with a plurality of elevator platforms adapted to be alternately raised and lowered, of mechanism for operating said elevator platforms comprising a drive shaft, gears carried by said drive shaft, a clutch member adapted to engage said gears with said drive shaft, a drum for winding thereon a cable leading to said elevator platforms, a gear on said drum in mesh with said first gears, the alternate engagement of said first gears with said drive shaft producing alternate reverse rotation of said drum whereby said platforms are raised and lowered in proper sequence, a pivotally mounted actuating arm for operating said clutch member, cables leading from the opposite ends of said actuating arm to a point near said platforms, a trip cam associated with said cables whereby said actuating arm may be swung about its pivotal point to operate said clutch member, and a locking member normally tending to engage in a groove provided in said actuating arm to lock said clutch member in neutral position.
17. In a hoist of the class described, the combination with a source of power, of mechanism for alternately elevating a plurality of elevator platforms, tripping means controlled by the movement of said platforms, an actuating arm operable by said tripping means to engage and disengage said source of power, and locking means normally tending to lock said actuating arm in power disengaging or neutral position.
18. In a hoist of the class described, the combination with a plurality of elevator platforms adapted to be alternately raised and lowered, of reversing mechanism for raising and lowering said elevator platforms comprising a drive shaft, a drum adapted to be driven by said drive shaft, a ring gear secured to said drum, gears loosely mounted on said drive shaft and meshing with said ring gear, and means controlled by the move-

ment of said elevator platforms for alternately engaging said gears with said drive shaft.

19. In a hoist of the class described, the combination with a plurality of elevator platforms adapted to be alternately raised and lowered, of mechanism for operating said elevator platform comprising a drive shaft having gears thereon normally disengaged therefrom, a drum, a ring gear connected thereto and in mesh with said gears, a shiftable clutch element, means for actuating said shiftable clutch element, and automatic means controlled by the position of said elevator platforms for operating said actuating means whereby said shiftable clutch element may engage either of said gears with said drive shaft.

20. In a hoist of the type described, the combination of a plurality of elevator platforms adapted to be alternately raised and lowered, of mechanism for operating said elevator platforms including a suspensory cable therefor, drum means for actuating said cable, an actuating arm, control cables extending to said actuating arm for operating the same according to the position of said elevator platforms, and clutch means operated by said actuating arm for controlling the direction of rotation of said drum means.

21. In a hoist of the type prescribed, the combination of a plurality of elevator platforms adapted to be alternately raised and lowered, of mechanism for operating said elevator platforms including a suspensory cable therefor, drum means for actuating said cable, an actuating arm, control cables

extending to said actuating arm for operating the same according to the position of said elevator platforms, and pawl and ratchet means controlled by said actuating arm for said drum means.

22. In a hoist of the type described, the combination of a plurality of elevator platforms adapted to be alternately raised and lowered, of mechanism for operating said elevator platforms including a suspensory cable therefor, drum means for actuating said cable, a drive for said drum means including reversing mechanism for reversing the rotation of said drum means, an actuating device for said reversing mechanism, and control cables extending to said actuating device for operating the same according to the position of said elevator platforms.

23. In a hoist of the type described, the combination of a plurality of elevator platforms adapted to be alternately raised and lowered, of mechanism for operating said elevator platforms including a suspensory cable therefor, drum means for actuating said cable, a drive for said drum means including reversing mechanism for reversing the rotation of said drum means, an actuating device for said reversing mechanism, control cables extending to said actuating device for operating the same according to the position of said elevator platforms and pawl means actuated by said actuating device and cooperating with said drum means to prevent accidental rotation of said drum.

In witness whereof, I hereunto subscribe my name this 15th day of August, A. D. 1925.

CARL ZETTERLUND
